SPRAY WAND

John William Mason, Hopewell Junction, N.Y., assignor
to Faultless Starch Company, Kansas City, Mo., a cor-
poration of Missouri

Filed Aug. 2, 1968, Ser. No. 13,015

Term of patent 14 years

Int. Cl. D23—01

U.S. Cl. D23—15

Fig. 1.

Fig. 2.

Fig. 4.

FIG. 1 is a side elevational view of a spray wand embodying my design;

FIG. 2 is a front elevational view of same;

FIG. 3 is a top end view of same; and

FIG. 4 is a bottom end view of same.

The dotted line portions shown in FIG. 1 depict a conventional hose for purposes of illustration only.

I claim:

The ornamental design for a spray wand, as shown and described.
